CLAIM

The ornamental design for a display screen with graphical user interface, as shown and described.

DESCRIPTION

FIG. 1 is a front view of a display screen with graphical user interface, showing a first embodiment of the new design; FIG. 2 is a second embodiment thereof; FIG. 3 is a third embodiment thereof; FIG. 4 is a fourth embodiment thereof; FIG. 5 is a fifth embodiment thereof; FIG. 6 is a sixth embodiment thereof; and, FIG. 7 is a seventh embodiment thereof.

The broken lines in the drawings illustrate the unclaimed display screen and unclaimed portions of the user interface and form no part of the claimed design.

1 Claim, 7 Drawing Sheets
